AUTOMOBILE IGNITION LOCK

Albert R. Lewellen, Detroit, Mich., assignor to
 General Motors Corporation, Detroit, Mich., a
 corporation of Delaware

Application December 14, 1926, Serial No. 154,791

17 Claims. (Cl. 200—19)

This invention relates to devices which tend to prevent the theft of an automobile and particularly to devices for locking the ignition timer in non-operating condition and for preventing removal of the timer from the frame of the engine which drives it.

One of the objects of the present invention is to provide a lock controlled device for preventing the non-cooperation of the ignition timer contacts.

10 A further object is to prevent access to the ignition timer housing so that the means which locks the ignition timer in non-operating condition cannot be manipulated so as to defeat the purpose of the ignition timer lock.

15 A still further object is to provide lock controlled means which will prevent cooperation of the timer contacts and will also prevent access to the devices which are used to attach the ignition timer to the frame of an engine which drives it, in order that the timer cannot be removed without mutilating some part of the engine frame or of the timer.

20 Further objects and advantages of the present invention will be apparent from the following description, reference being had to the accompanying drawing, wherein a preferred form of embodiment of the present invention is clearly shown.

In the drawing:

25 Fig. 1 is a fragmentary view, partly in section, of an ignition timer constructed in accordance with the present invention, the sectional view being taken on the line 1—1 of Fig. 2.

30 Fig. 2 is partly a sectional view on the line 2—2 of Figs. 1 and 4, and partly a longitudinal view of the lock controlled apparatus which is applied to the ignition timer.

35 Fig. 3 is a plan view of the timer with the distributor head removed.

40 Fig. 4 is a side view of the distributor housing cover having attached thereto certain of the elements which are used to secure the cover to the ignition timer housing.

45 Referring to the drawing, numeral 20 designates the frame of an engine which is supplied with ignition by ignition apparatus including the ignition timer to be described. The frame 20 is provided with an opening through the wall 21 thereof for receiving the shank 22 of a frame 23 which provides an ignition timer housing 24 and a housing 25 for the spark advance mechanism to be described. The wall 26 separating the housings 24 and 25 and the shank 22 provide bearings for the shaft 27 attached at its lower end to a gear 28 meshing with a gear 29 driven

by the engine. A shaft 30 which carries an ignition timer cam 31 and a distributor rotor 32 is received by the tubular upper end of the shaft 27 and is supported thereby so that the shaft 30 may rotate relative to the shaft 27. The shafts 27 and 30 are drivingly connected by means which will produce annular displacement of the shaft 30 relative to the shaft 27. This means includes a cross pin 33 which is received by a straight longitudinal slot 34 in the shaft 30 and by diametrically opposite helical slots in the shaft 27, one of these helical slots being indicated by numeral 35. The ends of pin 33 are supported by a grooved collar 36 which is moved longitudinally by a lever 37 attached by a screw 38 to a shaft 39 which may be manually operated so as to control the position of the shaft 30 relative to the shaft 27. In this way the timing of the ignition spark may be controlled as will be apparent from the description of the ignition timer 20 which follows.

45 A breaker lever plate 40 is secured in any suitable manner to the bottom of the timer housing 24 and insulatingly supports an ignition breaker lever 41 carrying a contact 42 which normally cooperates with a relatively stationary contact 43 in order to control the ignition circuit. The contact 42 is separated from the contact 43 when the timer cam 31 engages a rubbing block 44 carried by the lever 41.

50 The ignition timer 24 is enclosed by a cover 50 which is received by an annular recess providing a shoulder 51 which supports the cover 50. A portion of the cover projects above the upper edge 52 of the housing 24 and provides means for locating an ignition distributor head 53 centrally of the timer shaft 30. It will be understood that the distributor head 53 may be of any conventional type having stationary contacts which cooperate with a movable contact, 40 not shown, carried by the distributor rotor 32. The cover 50 is provided with an extension 54 located above the plane of the main portion of the cover and extending in a notch 55 provided by the distributor head 53 so as to locate the distributor head angularly with respect to the shaft 30.

55 The cover 50 is secured by riveting or spot welding to a plate 56 having downwardly extending resilient ears 57 which are received by notches 58 provided by the housing 24 and provided also with projections 59 and 60, having notches 61 and 62 respectively. The notches 61 and 62 receive the inwardly projecting ends 63 and 64 respectively of screw pins 65 and 66 respectively. 55

It is apparent therefore that the cover 50 may be placed upon the housing 24 as shown in Fig. 1, the pins 65 and 66 being initially out of vertical alignment with the extensions 59 and 60 of the plate 56. When the plate 56 is turned so that the resilient fingers 57 will be received by the notches 58 of the housing 24, the pin ends 63 and 64 will be received by the notches 61 and 62 respectively. Therefore the cover 50 cannot be removed unless it is turned back to the position in which the pin ends are free of the notches. To prevent turning of the cover 50 there is provided a stud 70 which is movable within a hole 71 provided by the projection 59 of the plate 56 and which is provided with a head received by a recess 72 provided in the side of the housing 24. The stud 70 is carried by a resilient arm 73 attached by rivets 74 to an extension 75 of the plate 56. The resilient arm 73 is biased so that it tends to maintain the stud 70 out of the recess 72. The arm 73 is located in the plane of a portion 41a of the lever 41. When the lever 41 is maintained in the position shown in Fig. 2, the portion 41a will cooperate with the arm 73 to move the stud 70 into the recess 72 thereby preventing rotation of the plate 50 and removal thereof from the housing 24.

Lock controlled means is provided for preventing non-cooperation of the contacts 42 and 43 by maintaining the breaker lever 41 into position shown in Fig. 2 in which the movable contact 42 is maintained out of contact with the stationary contact 43 regardless of the rotation of the cam 31. This means includes a rod 80 adapted to engage an extension 81 of the lever 41 and slidable through a bushing 82 which is permanently attached to the housing 24. The bushing 82 provides a recess 83 for receiving one end of a metallic, flexible armor-tube 84, the other end of which is secured to a sleeve 85 slideable within a recess 86 provided in a lock frame 87. The armor-tube 84 encloses a Bowden wire tube 88 attached at one end to a washer 89 located within the recess 86 of the bushing 82 and attached at its other end to a partition 90 separating the recess 86 from a recess 91. The Bowden wire tube 88 encloses a Bowden wire 92 having one end attached to the rod 80 and the other end extending into the recess 91 and projecting through a washer 93 and having its end 94 bent over against one side of the washer 93. This end 94 is urged by a spring 95 against the inner end of the barrel 96 of the automobile type, pin tumbler lock. The details of this lock are not all shown but it will be understood that the proper key will produce the rotation of a key cylinder 97 which in turn will draw a spring pressed plunger 98 from a recess 99 in the side of the lock frame 87. When this occurs, the spring 95 will be released to effect the outward movement (upward as viewed in Fig. 1) of the lock barrel 96 relative to the lock frame 87. This relative movement is limited by a pin 100 attached to the lock frame 87 and extending into a slot 101 provided by the lock barrel 96. Removal of the sleeve 85 from the recess 86 is prevented by a sleeve 102 through which the sleeve 85 is slideable, the sleeve 102 being attached by a screw pin 103 to the lock frame 87. The sleeve 102 is provided with a flange 104 adapting it to be attached by screws 105 to the instrument board 106 of an automobile. A finishing plate 107 through which the lock barrel is slideable is also attached by the screws 105 to the instrument board 106. Since one end of the tube 84 is fixed

and the other end is slidably connected with a fixed part, manipulation of the tube tending to change its curvature from normal, as installed, may take place without substantially affecting the Bowden wire enclosed thereby.

To render the ignition timer operative by permitting the timer contacts to cooperate normally, the plunger 98 is retracted from the recess 99 by turning the key cylinder 97 by a suitable key. As previously mentioned, the spring 95 will be released and will move the barrel 96 upwardly as viewed in Fig. 2 and will consequently move the Bowden wire 92 and the rod 80 upwardly thereby permitting the contact 42 to engage the contacts 43, due to the action of a helical spring 15 45 which tends to urge the lever 41 toward the cam 31. The resilient arm 73 being released by the retraction of the lever 41, the stud 70 will be drawn from the recess 72 so that the cover 50 may be removed from the timer housing if desired. 20 To lock the timer in non-operating position, the operator will press the lock barrel 96 inwardly until the plunger 98 snaps into the recess 99 which holds the barrel 96 in locked position. This movement of the barrel 96 will cause the rod 25 30 35 40 45 50 55 60 65 70 75 80 85 90 95 100 105 110 115 120 125 130 135 140 145 150 155 160 165 170 175 180 185 190 195 200 205 210 215 220 225 casing normally operable to control the timing of the ignition and means for retracting said member to an inoperative position, for securing said cover against removal from said casing and for preventing access to said timer attaching means.

3. An anti-theft device for automobiles comprising an ignition timer including make-and-break contacts, means whereby the engine operates said timer, means for attaching the timer to the engine frame, and lock controlled means for preventing cooperation of the timer contacts and for preventing access to said timer attaching means.

4. An anti-theft device for automobiles comprising an ignition timer having a movable contact on a breaker lever engageable with a relatively stationary contact, means whereby the engine operates said timer, means for attaching the timer to the engine frame, and lock controlled means for moving the movable contact out of engagement with the stationary contact and for holding it in such position, and for preventing access to said timer attaching means.

5. An anti-theft device for automobiles comprising an ignition timer adapted to be driven by the engine and having a housing containing make-and-break contacts, a breaker lever supporting one of the contacts, a cover for the housing, means for attaching the housing to the frame of the engine, and lock controlled means for preventing access to the timer attaching means, for preventing removal of the cover, and for preventing cooperation of the contacts.

6. An anti-theft device for automobiles comprising an ignition timer adapted to be driven by the engine and having a housing containing make-and-break contacts, a cover for the housing, means for attaching the housing to the frame of the engine, means to prevent removal of the timer attaching means, said means being accessible through the housing only when said cover is removed, and lock controlled means for preventing cooperation of the timer contacts and for preventing removal of the cover.

7. An anti-theft device for automobiles comprising an ignition timer adapted to be driven by the engine and having a housing containing make-and-break contacts, a cover for the housing, means for attaching the housing to the frame of the engine, means to prevent removal of the timer attaching means, said means being accessible through the housing only when said cover is removed, and lock controlled means for preventing removal of the cover.

8. An anti-theft device for automobiles comprising an ignition timer adapted to be driven by the engine and having a housing containing make-and-break contacts, said housing having a shank, adapted to be received by an opening in the frame of the engine, a locking member extending from the frame into the shank to prevent removal of the housing from the frame and manually adjustable to permit removal of the housing, a second member for engaging the first locking member to prevent adjustment thereof, said second member being accessible through the timer housing, and lock controlled means for preventing access to the second member.

9. An anti-theft device for automobiles comprising a housing for enclosing timing and distributing devices, a plate for dividing the housing into timer and distributor chambers; a member within the timer chamber normally operable to control the ignition timing, and means for moving said member to an inoperative position and for securing said plate against re-

moval from the housing, when said member is moved.

10. An anti-theft device for automobiles comprising an ignition apparatus having a timer and a distributor therefor, a housing for said apparatus, a cover plate for the timer separating the housing into a distributor chamber and a timer chamber, make-and-break contacts in the timer chamber, and lock controlled means for locking the cover against removal and for preventing cooperation of the timer contacts when said means is operated to lock said cover.

11. An anti-theft device for automobiles comprising an ignition apparatus having a timer and a distributor therefor, a housing for said apparatus, a cover plate for the timer separating the housing into a distributor chamber and a timer chamber, a circuit interrupter in the timer chamber, said interrupter including a cam-operated circuit breaker lever, and lock controlled means for holding the lever in circuit open position and for securing the cover plate against removal, while the lever is held in such position.

12. An anti-theft device for automobiles comprising, in combination, a timer housing, a cover for said housing, a member within the housing normally operable to control the ignition timing, means for moving said member to an inoperative position, and a device moved by said member as the latter is moved into inoperative position to prevent removal of the cover from the housing.

13. An anti-theft device for automobiles comprising an ignition timer having a movable contact carried by a lever and engageable with a stationary contact, a housing for the contacts and lever, a cover for the housing, lock controlled means for holding said lever in such position that the contact carried thereby is out of engagement with the fixed contact, and means actuated by the lever when moved to such position for preventing removal of the cover.

14. An anti-theft device for automobiles comprising an ignition timer having a movable contact carried by a lever and engageable with a stationary contact, a housing for the contacts and lever, said housing having an opening in the side wall thereof, a cover for the housing and carrying a member movable into said opening in the housing wall to lock the cover against removal from the housing, lock controlled means for moving said lever to position to hold the movable contact out of engagement with the stationary contact and means whereby said lever holds said locking member in said opening when the lever is moved to such position.

15. An anti-theft device for automobiles comprising, in combination, a timer housing, a cover for said housing, a member within the housing normally operative to control the ignition timing, interlocking means provided by the cover and housing, said interlocking means being releasable by partial rotation of the cover, and lock controlled means for preventing rotation of the cover, whereby the cover and housing are held in interlocked condition as long as lock controlled means is operative.

16. An anti-theft device for automobiles comprising, in combination, a timer housing, a cover for said housing, a member within the housing normally operative to control the ignition timing, interlocking means provided by the cover and housing, said interlocking means being re-

leasable by partial rotation of the cover, and lock controlled means for moving said member to inoperative position, and for preventing rotation of the cover, whereby the cover and housing are held in interlocked relation when said member is in inoperative position.

17. An anti-theft device for automobiles comprising, in combination, a timer housing, a cover for said housing, a member within the housing normally operative to control the ignition timing, interlocking means provided by the

cover and housing, said interlocking means being releasable by partial rotation of the cover, means for moving said member to inoperative position, and a device moved by said member into position for preventing rotation of said cover, as said member is moved to inoperative position, whereby said cover and housing are held in interlocked relation while said member is held in inoperative position.

ALBERT R. LEWELLEN.
